MOLDING PRESS HEAD CONTROL SYSTEM

Filed Sept. 5, 1957

INVENTOR

Walter L. Floehr

BY John G Batchelder

ATTORNEY

the valve 22 is actuated to the position shown in Fig. 1 to connect the pressure source 24 to the chamber 15. Fluid under pressure enters the chamber 15 and expands the flexible diaphragm into engagement with the sand, and as further pressure is supplied to the chamber 15, the flexible diaphragm 14 compacts the sand within the flask F about the pattern P.

After a predetermined pressure has been achieved within the chamber 15, the valve 22 is actuated to disconnect pressure source 24 from the chamber 15 and connect the chamber 15 to the duct 30. Fluid under pressure passes from chamber 15 into the duct 30 and into the interior of the duct section 50. From the duct section 50, the fluid under pressure may flow into the interior of both ducts 46 and 48. When the pressure within the duct 46 begins to rise due to the flow of pressurized air from the press head, plate 58 of the flap valve is moved upwardly into the dotted line position of Fig. 2, thereby opening the interior of the duct 46 to the atmosphere through the duct 56. In this manner, the pressure within chamber 15 is rapidly reduced to atmospheric pressure.

As disclosed in the drawings, plate 58 is gravitationally biased toward its closed position, and when the pressure within the chamber 15, and hence ducts 30, 50, and 46 approaches atmospheric pressure, the flap valve automatically closes by the fall of plate 58 to its full line position in Fig. 2. In certain applications, it may be desirable to use a spring biased valve closure member. After the valve 57 closes, the constantly driven vacuum pump 28 continues to reduce the pressure within chamber 15 to below atmospheric pressure and thereby retracts the flexible diaphragm 14 upwardly away from the sand within the flask F. When the diaphragm is retracted, the traverse car T containing the compacted mold flask is removed and a fresh traverse car T is moved into position beneath the press head 10 for a repetition of the foregoing operation.

Since the vacuum pump 28 is constantly driven, it can be appreciated that the foregoing operation may be rapidly repeated. The rapid lowering of the pressure within chamber 15 by venting this chamber to the atmosphere through the outer duct 46, duct 56 and the flap valve permits the pressure within chamber 15 to be rapidly reduced below atmospheric without requiring a substantial increase in the capacity of the vacuum pump 28.

While I have described but one embodiment of my invention, it will be apparent to those skilled in the art that the disclosed embodiment is capable of modification. Therefore, the foregoing description is to be considered exemplary rather than limiting and the true scope of my invention is that defined in the following claims.

I claim:

1. In combination with a mold press head having pressure responsive means for compacting sand within a mold flask; a pressure source for moving said pressure responsive means to a sand compacting position and including a first duct means, a vacuum source for retracting said pressure responsive means from said sand compacting position and including a second duct means, valve means for selectively connecting either said first or said second duct means to said press head, and means for venting said second duct means to atmospheric pressure when the pressure in said second duct exceeds a predetermined pressure.

2. In combination with a mold press head having pressure responsive means for compacting sand within a mold flask; a pressure source for moving said pressure

responsive means to a sand compacting position and including a first duct means, a vacuum source for retracting said pressure responsive means from said sand compacting position and including a second duct means, valve means for selectively connecting either said first or said second duct means to said press head, a valve in said second duct means for venting said second duct means to atmospheric pressure, and means for closing said valve when the pressure in said second duct means approaches atmospheric pressure.

3. The combination recited in claim 2 wherein said second duct means includes an inner duct connected to said vacuum source, an outer duct in communication with said inner duct, and means connecting said valve to said outer duct.

4. In combination with a mold press head having pressure responsive means for compacting sand within a mold flask; a pressure source for moving said pressure responsive means to a sand compacting position and including a first duct means, a constantly driven vacuum pump for retracting said pressure responsive means from said sand compacting position, second duct means connected to the inlet of said vacuum pump, valve means for selectively connecting either of said first and said second duct means to said press head to operate said pressure responsive means, and means for venting said second duct means to atmospheric pressure when the pressure in said second duct exceeds a selected pressure.

5. In combination with a mold press head having pressure responsive means for compacting sand within a mold flask; a pressure source for moving said pressure responsive means to a sand compacting position and including a first duct means, a constantly driven vacuum pump for retracting said pressure responsive means from said sand compacting position, second duct means connected to the inlet of said vacuum pump, valve means for selectively connecting either of said first and said second duct means to said press head to operate said pressure responsive means, a valve in said second duct means for venting said second duct means to atmospheric pressure, and means for closing said valve when the pressure in said second duct means approaches atmospheric pressure.

6. In combination with a mold press head having pressure responsive means for compacting sand within a mold flask; a pressure source for moving said pressure responsive means to a sand compacting position and including a first duct means, a constantly driven vacuum pump for retracting said pressure responsive means from said sand compacting position, an inner duct connected to the inlet of said vacuum pump, an outer duct surrounding said inner duct and in communication therewith, a normally closed valve mounted on said outer duct for venting said outer duct to atmospheric pressure, and means for opening said valve when the pressure within said outer duct is above a predetermined pressure.
